GLASS-BEVELING MACHINE.

1,205,260.

Specification of Letters Patent. Patented Nov. 21, 1916.

Application filed February 8, 1916. Serial No. 76,908.

To all whom it may concern:

Be it known that I, Владыславъ Йосифъ Поровски, subject of the Czar of Russia, and a resident of the city of New York, 5 borough of Brooklyn, in the county of Kings and State of New York, have invented a new and Improved Glass-Beveling Machine, of which the following is a full, clear, and exact description.

10 My invention relates to a glass-beveling machine, particularly adapted for the beveling of disks.

An object of the invention is to provide a simple, strong and inexpensive beveling 15 machine which is automatic in its action and in which the disks to be beveled are maintained in position while beveled by pneumatic means.

A further object of the invention is to 20 provide a glass-beveling machine in which the disk when beveled is automatically disengaged from the grindstone in such a way that the same can be easily removed without arresting the machine, and a disk to be 25 beveled placed into position to be engaged by the grindstone.

With the above and other objects in view, the nature of which will more fully appear as the description proceeds, the invention 30 consists in the novel construction, combination and arrangement of parts as herein fully described, illustrated and claimed.

In the accompanying drawings, forming 35 part of the application, similar characters of reference indicate corresponding parts in all the views.

Figure 1 is a plan view of my machine; Fig. 2 is an axial section on line 2—2, Fig. 1; Fig. 3 is a rear end elevation; Fig. 4 is a 40 front elevation of a circular, beveled mirror the bevel of which was formed on my machine; and Fig. 5 is a cross section therethrough.

Referring to the drawings, 7 is the bed, 45 preferably of rectangular contour and provided at the front with spaced lugs 8. The bed is mounted on a center pivot 7' secured into the bed support, which has also articulated slots 8' engaged by screws 9' by which 50 the bed may be locked to the support after it has been adjusted on the pivot 7'. A frame 9 is mounted to rock on adjustable center bolts 10 carried by the lugs. The frame 9 has an arm 11 extending rearwardly 55 from the bed and from which a bearing por-

tion 12 rises to coöperate with the bearing portion 13 of the frame. A hollow spindle 14 is revolvably mounted in the bearing portions 12 and 13. The end of the spindle projecting in front of the bed 7 is threaded 60 to receive an interchangeable, apertured, flanged head 15 which has at the margin a ring 16 of yielding material, the purpose of which will appear hereinafter.

The rear end of the spindle is provided 65 with a collar 17 which forms the abutment for the packing material 18 located in a stuffing box 19 forming part of a socket 20. The socket 20 has a valve-controlled extension 21 to which a flexible conduit 22 in the 70 shape of a hose is connected. Through this conduit air may be exhausted from the hollow spindle. Coöoperating with the stuffing box is a packing gland 23 having an extension 24 adapted to engage the arm 11 of the 75 frame, whereby the socket is prevented from revolving when the spindle 14 is revolved through the medium of a stepped pulley 25 secured to the spindle. The spindle has a limited axial displacement in the bearing 80 portions 12 and 13 resisted by a split washer 25' which is located between a stop collar 26 and the bearing portion 13. The stop collar is preferably in the shape of a pulley.

It will be noted that gravity will move the 85 frame 9 on its pivot, tending to raise the front end of the spindle. This tendency is resisted by a cam 27 which has a spiral periphery 28. The arm 11 carries a roller 29 mounted to ride on the periphery of the 90 cam. The cam is free to turn on a shaft 30. A clutch portion 31 is constrained to rotate 95 with the shaft. A coöoperating clutch portion 32 forms part of the cam, and it is normally maintained in engagement with the cam portion 31 by a coil spring 33 mounted on the shaft 30. The shaft 30 is supported in suitable bearings 34 on the bed 7.

A worm wheel 35 is constrained to rotate 100 with the shaft 30. In mesh with the wheel 35 is a worm 36 with which a worm wheel 37 is constrained to rotate. A worm 38 in mesh with the wheel 37 is provided with a stepped pulley 39 which may be driven from any suitable source. The worm wheel and 105 worms constitute the driving means for the shaft 30, whereby for a single revolution of the shaft 30 a predetermined number of revolutions of the spindle 14 is obtained. The cam 27 is provided with a cut-out 110

into which the roller 29 is adapted to drop when said cut-out comes under the roller. The bottom 41 of the cut-out is beveled or inclined so that the weight of the frame 5 brings the roller 29 into engagement with the bottom 36 of the cut-out, compresses the spring 33 and, consequently, disengages the clutch portion 32 from the clutch portion 31, thus stopping the revolution of the cam 10 and raising the feed of the spindle. The cut-out 40 is formed between the highest point *a* and the lowest point *b* of the spiral 28.

When the roller 29 is dropped into the 15 cut-out 40 of the cam, the front end of the spindle 14 will be raised from the grindstone 42. If a glass disk 43 (as shown in Figs. 4 and 5) is brought against the ring 16 the suction created in the spindle through 20 the hose 22 will retain the disk 43 against the head 15. By bringing the roller 29 into engagement with the point *b* of the cam the clutch portions are permitted to engage, thus setting the cam 27 into rotation. The 25 spiral periphery gradually feeds the margin of the disk 43 against the grindstone 42, thus the bevel of the disk 44 is gradually formed. When the cam reaches the highest point *a*, the margin of the disk is perfectly 30 beveled (as shown in Figs. 4 and 5), and as the roller comes over the cut-out it drops thereinto, automatically forcing the clutch out, thus stopping the spindle's feed and simultaneously clearing the disk from the 35 grindstone. The so-beveled disk can then be removed from the spindle and a new un-beveled disk substituted therefor, and the operation repeated.

To relieve the shaft 30 and the connections therefor from shocks when the frame drops into the cut-out, a buffer 45 is provided for the bed 9. The buffer is in the shape of a dash-pot. It consists, preferably, of a housing 46 having a piston 47 therein, 45 the piston rod 48 of which is provided with a head which is cushioned to be engaged by a toe 49 extending from the frame 9. A vent 50 is provided in the housing so that the falling of the frame 9 is gradual, the 50 buffer 45 forming a yielding or cushioning means for the frame for eliminating shocks in the machine. It is self-evident that with a change of the disk size the head 15 must be changed.

55 While I have described the principle of operation, together with the apparatus which I now consider to be the best embodiment thereof, I desire to have it understood that the apparatus shown is merely illustrative and that such changes may be made as are within the scope of the appended claims.

I claim:

1. In a machine of the class described, a 60 revoluble disk carrier, means for pneumati-

cally retaining a disk on the carrier, means for revolving the carrier, a revolving grindstone, and means for feeding the carrier to bring the margin of the disk into engagement with the stone, said feeding means 70 having means for displacing the carrier to clear the disk from the stone after a predetermined bevel has been formed on the disk.

2. In a machine of the class described, a 75 revoluble disk carrier, a rocking frame supporting the disk carrier, means for pneumatically retaining a disk on the carrier, means for revolving the carrier, a revoluble grindstone, and means for rocking the 80 frame to feed the carrier toward the stone, said means for rocking the frame including means for clearing the carrier from the stone after a predetermined feed of the carrier. 85

3. In a machine of the class described, a hollow spindle mounted to rock longitudinally, pneumatic means for creating a suction in the spindle whereby a disk is retained by the spindle, a revolving grindstone, and a spiral cam for rocking the spindle to bring the margin of the disk into engagement with the stone, said cam having means for rocking said spindle so as to move the disk on the spindle away from the 95 stone after the disk has been fed through a predetermined distance toward the stone. 90

4. In a machine of the class described, a bed, a frame pivotally mounted on the bed, a hollow spindle carried in said frame, pneumatic means associated with one end of the spindle for creating a vacuum therein, a disk-receiving head associated with the other end of the spindle, means for revolving the spindle, a revoluble grindstone adjacent the head, the action of gravity on the frame tending to move the head of the spindle away from the stone, a cam having a peripheral, spiral surface, a roller carried by the frame engaging the peripheral surface of the cam, means for revolving the cam whereby the frame is moved on its pivot and whereby the margin of the disk is fed against the grindstone, said cam having a cut-out into which said roller is adapted to drop whereby the head is cleared from the grindstone, substantially as and for the purpose set forth. 110

5. In a machine of the class described, a 120 base, a frame pivotally supported thereupon, a hollow spindle rotatably mounted in said frame, pneumatic means associated with one end of said spindle for exhausting the air from the hollow of the spindle, a disk carrier associated with the other 125 end of the spindle, a revoluble grindstone adjacent the carrier, the force of gravity upon the frame tending to move the head away from the grindstone, a roller carried by said frame, a cam engaging the 130

5 roller, means for revolving the cam, a clutch for coupling the cam to the revolving means, the revolving of said cam causing the frame to move on its pivot so as to bring the margin of the disk into engagement with the grindstone, said cam having a cut-out for receiving the roller whereby the disk is cleared from the stone and the engagement of the roller with the cut-out, causing the 10 uncoupling of the cam from the revolving means.

6. In a machine of the class described, a 15 gravitationally-operable frame, a disk having a spiral periphery, a roller carried by the frame resting on the periphery of the disk, means for revolving the disk whereby the frame is gradually raised, said disk having a cut-out into which the roller is adapted to drop, and a revoluble disk carrier on the 20 frame.

7. In a machine of the class described, a 25 gravitationally-operable frame, a disk having a spiral periphery mounted to rotate, means for revolving the disk, yielding means for coupling the disk to the revolving means, a roller carried by the frame engaging the spiral periphery of the disk, said disk having a cut-out into which the roller is adapted to drop, said cut-out being so shaped that the drop of the roller thereinto uncouples 30 the disk from the revolving means, and a revoluble disk carrier on the frame.

8. In a machine of the class described, a 35 gravitationally-operable frame, a revoluble shaft, a train of gear for driving said shaft, a disk free to revolve on said shaft, means for coupling the disk to the shaft, a resilient member tending to maintain the disk

coupled to the shaft, said disk having a spiral periphery and a cut-out, a roller carried on said frame engaging the periphery and adapted to drop into the cut-out of the disk when the same comes under the roller, said cut-out having a beveled portion adapted to be engaged by the roller, whereby the 40 disk is moved on the shaft to counteract the resilient member, thereby uncoupling the disk from the shaft, a revoluble disk carried on the frame, and pneumatic means associated with the disk carrier for retaining 45 the disk on the carrier.

9. In a machine of the class described, a 50 revoluble disk carrier, a rocking frame supporting the disk carrier, means for pneumatically retaining the disk on the carrier, 55 means for revolving the carrier, a revoluble grindstone, resilient means normally tending to move the disk carrier toward the grindstone, and means for rocking the frame whereby the disk carrier is moved to and 60 from the grindstone.

10. In a machine of the class described, a 55 gravitationally operable frame, a cam for operating the frame, means for actuating the cam, means normally coupling the actuating means to the cam, and means for uncoupling the cam from the actuating means operable when said frame is moved under the action of gravity.

In testimony whereof I have signed my 70 name to this specification in the presence of two subscribing witnesses.
